(57) **CLAIM**

The ornamental design for a hat, as shown and described.

DESCRIPTION

FIG. 1 is a left side perspective view of the hat of the present design;

FIG. 2 is a rear elevational view of the hat of FIG. 1;

FIG. 3 is a front elevational view of the hat of FIG. 1;

FIG. 4 is a bottom plan view of the hat of FIG. 1;

FIG. 5 is a top plan view of the hat of FIG. 1; and,

FIG. 6 is a front perspective view of the hat of FIG. 1 as worn on a person's head.

The broken line showing of the human form in FIG. 6 is for illustrative purposes only and forms no part of the claimed design.
